UNITED STATES PATENT OFFICE

EDWARD B. RYNEAR, OF UPPER DUBLIN, ASSIGNOR TO WILLIAM H. GREEN,
OF PHILADELPHIA, PENNSYLVANIA.

IMPROVEMENT IN INJECTORS.

Specification forming part of Letters Patent No. 174,578, dated March 7, 1876; application filed September 22, 1875.

To all whom it may concern:

Be it known that I, EDWARD B. RYNEAR, of Upper Dublin, Montgomery county, Pennsylvania, have invented certain Improvements in Injectors, of which the following is a specification:

The objects of my invention are, first, to provide an injector for steam-boilers with a simple and efficient device for lifting a volume of water at the commencement of the operation, and, second, to so construct the injector that the admission of both steam and water can be controlled by one operating spindle. These objects I attain in the manner which I will now proceed to describe, reference being had to the accompanying drawing, in which—

Figure 1 is a longitudinal vertical section of my improved injector; Fig. 2, the same with the working parts in a different position; Fig. 3, a transverse vertical section on the line 1 2, Fig. 1; and Fig. 4, a transverse vertical section on the line 3 4, Fig. 1.

A is the casing of the injector, having the usual steam-inlet B, water-inlet D, and overflow chamber E, all of which communicate with the central opening, of varying diameter, which extends from end to end of said casing. This openly communicates at one end with a pipe leading to the boiler, and is closed at the opposite end by a tapering plug, a, attached to or forming part of a spindle, b, threaded at its inner end, the said plug a being retained in position by means of a nut, d, so as to prevent any but a rotary movement of the spindle b. The threaded end of this spindle is adapted to a threaded opening in a hollow plug, F, which fits snugly, but so as to slide freely, in the central opening of the casing A, and is caused to move longitudinally by operating the said spindle b, a lug, f, at the end of the plug working in a slot in the casing A, and serving to prevent the turning of the said plug F. To the interior of the plug F, a short distance from the outer end of the same, is adapted a screw-plug, e, carrying a tapering nozzle, G, which extends to or beyond the end of the plug F, for a purpose described hereafter.

The nozzle G communicates at its enlarged end with a chamber, i, formed in the end of

the plug F, and bounded at one end by the end of the screw-spindle b, and at the other by the screw-plug e, and this chamber also communicates through perforations m with the steam-inlet B of the injector.

The plug F is reduced in diameter at k so as to form an annular valve-face, which is adapted to an annular valve-seat, l, formed in the casing A, and immediately adjacent to this valve k the plug F is provided with openings, n, which, under the circumstances described hereafter, establish a communication between the steam-inlet B and the central opening of the plug.

The inner end s of the plug F is made tapering, and the end of the opening p of the injector adjacent to the end of the plug is flared outward at a corresponding angle, the parts being so arranged that when the valve k is in contact with its seat there shall be a slight annular space, x, between the end of the plug and the flared portion of the opening p.

The operation of the above-described injector is as follows:

The parts being in the position shown in Fig. 1, steam is admitted at the inlet B and passes through the perforations m and into the nozzle G, from the end of which it issues in a fine jet, which passes through the opening p, and, owing to the check-valve in the exit-pipe, escapes at the overflow-chamber E. This jet produces a partial vacuum in the water-chamber D, owing to the communication between the same and the opening p through the annular space x, and the water rising in the chamber D passes through this space and is discharged from the overflow-chamber.

The plug F is now moved rearward by operating the spindle b, thus exposing the openings n and permitting an increased volume of steam to enter the hollow plug F, the same movement also widening the annular space x (as shown in Fig. 2) and permitting the entrance of an increased volume of water, the two combining in the opening p and passing thence through the exit-opening into the pipe communicating with the boiler.

It will be seen that by the above-described arrangement the admission of both steam and water is under the control of the spindle b, by

operating which the volume of both can be increased or diminished at pleasure.

In cases where it is not necessary to lift the supply of water for the injector, the nozzle G and annular valve k may be dispensed with, and the tapering end s of the plug F may act as a valve, and the flaring end of the opening p as a valve-seat, for preventing the access of water, the openings n in such case being closed by the edge l of the casing before the end s of the plug reaches its seat.

Fig. 5 shows a modification of my invention in which the end of the plug F and the end of the opening p are made partly tapered and partly straight, the object of this arrangement being to permit a rearward movement of the plug sufficient to slightly expose the openings n before commencing to enlarge the area of the water-entrance.

I claim as my invention—

1. The combination of the longitudinally-adjustable plug F, its openings n and end s, with the valve-face l and opening p in the casing, all constructed and operating substantially as set forth, so as to regulate the admission of both steam and water by one movement of the plug.

2. The combination of the nozzle G with the hollow plug F, its perforations m, openings n, and tapered end s, the latter being arranged in respect to the tapered opening p of the injector as herein set forth.

In testimony whereof I have signed my name to this specification in the presence of two subscribing witnesses.

EDWARD B. RYNEAR.
